UNITED STATES PATENT OFFICE.

CLIFFORD F. BOYER, OF WEBSTER GROVES, MISSOURI.

REFRIGERATOR.

Application filed June 24, 1925. Serial No. 39,258.

This invention relates to improvements in refrigerators, and consists in the novel construction hereinafter disclosed.

An object of the invention is to improve the arrangement of the refrigerating chambers, the drains therefrom and the circulating passages to increase the cooling efficiency by obtaining the maximum result from the refrigerant.

10 Another object of the invention is to arrange the refrigerating chambers in such way that the temperature of the refrigerator case will be substantially uniform throughout.

15 Additional advantageous features will be apparent from the following description of the invention taken in connection with the accompanying drawings, in which

Fig. 1 is a front elevation of a refrigerator embodying the invention.

Fig. 2 is a cross section substantially on the line 2—2 of Fig. 1.

Fig. 3 is a vertical section through the refrigerator substantially on the line 3—3 of 25 Fig. 1.

Fig. 4 is a vertical section on the line 4—4 of Fig. 1.

Fig. 5 is a longitudinal section on the line 5—5 of Fig. 2.

30 Fig. 6 is a detailed view of the drip pan. Fig. 7 is a detailed view of a connection between the drain conduits.

In the embodiment illustrated in the drawing the invention is shown as incorporated 35 in a display case refrigerator having the display case centrally located and the refrigerating chambers at each end, although it will, of course, be understood that the features of the invention may be embodied in 40 other structure. The refrigerating chambers are of duplicate construction and in the description of one it will be understood that it applies also to the other refrigerating chamber. The case in which the structure is 45 embodied comprises generally a rectangular box having a bottom wall 1, end walls 2, a front wall 3 incorporating central glass panels 4, and a back wall 5. The end portions of the case comprise the refrigerating 50 compartments and are equipped with doors 6. The central part of the case comprises the display section and is equipped with doors 7. The top 8 has central glass panels 9. Within the display section of the case 55 are longitudinal shelves 10 and 11, the shelf 10 being elevated and inclined downwardly

from the back to the front of the case, and the shelf 11 being arranged parallel with the shelf 10 and is also inclined from the back wall of the case to the front wall. The 60 shelf 11 is elevated so that the forward lower edge is spaced a distance considerably above the bottom wall 1, and so that it will be in line of vision through the panels 4.

All of the walls of the case are of double 65 thickness and are insulated in the usual manner. At each end of the case are blocks 12 having the upper surfaces thereof inclined inwardly toward the center of the case.

The refrigerating chambers are mounted 70 above the blocks 12 and each comprises an open top container formed from front and back walls 13, a bottom wall 14 and end walls 15 and 16 respectively. The walls 13 incline inwardly toward the center so that 75 there is a greater space between the front and back walls of the case adjacent to the wall 16 than there is at the ends of the case adjacent to the wall 15. The wall 15 is extended on its side and top edges forming a 80 U-shaped flange 17 that fits closely against the sides of the case when the refrigerating chamber is in place in the case, thus preventing circulation around the side edges of the case and across the top thereof and forcing 85 the currents of cool air downwardly below the refrigerating chambers, the air being deflected inwardly by the inclined surfaces 90 of the blocks 12.

In the embodiment shown the refrigerating 95 chamber is of a pull-out type, being mounted upon tracks 18, the rails of which are supported by the front and rear walls of the case, the refrigerating chambers being arranged in alinement with the doors 6 so 95 that they may be pulled out of the case for filling.

Each of the refrigerating chambers has 100 incorporated therein a series of baffle walls for deflecting currents of air for distribution 100 in the main refrigerating case. These baffle walls include a vertically disposed transverse wall 19 extending between the walls 13 and substantially intermediate the walls 15 and 16. The wall 19 connects with a horizontally 105 disposed but downwardly inclined wall 20 running from the lower edge of the wall 19 to the plane of the wall 16. Connected with the wall 19 and running forwardly to the wall 16 are parallel walls 21 which, with an 110 upwardly inclined bottom wall 22, form a small rectangular chamber in which is set a

series of downwardly inclined baffle walls 23, said walls 23 running parallel with each other and being spaced apart as clearly illustrated in Fig. 5. Intermediate the walls 20 and 22 are downwardly inclined baffle walls 24. The wall 19 has a series of perforations or openings 25 that communicate the outer chamber around the walls 19 and 21 with the space between the walls 20—22—23 and 24. 5 It will be observed that the arrangement of the baffle walls described forms two supplemental chambers on each side of the walls 21 and between said walls 21 and the respective back and front walls 13, so that when the 10 refrigerant container is filled with the refrigerant, preferably in the form of ice and salt and said compartments defined by the walls 13, 21, 22, 16 and 19 are also filled with the refrigerant, there will be a refrigerating area near the top of the case formed by the walls of said supplemental refrigerant compartments which deflect cool currents downwardly toward the center of the case and at an elevation substantially above the 15 bottom of the case, thus providing a circulation of cool currents across the top of the display compartment of the refrigerator. It will also be noted that the walls 24 provide for a transverse distribution of cooling currents of air substantially intermediate of the top and bottom of the case and entirely 20 across the same.

When the ice in the refrigerant containers melts the brine will flow through the perforations 25 onto the wall 22 and a quantity will be trapped within the compartment between said supplemental refrigerant compartments, providing for maintaining a part 25 of the refrigerating material near the top of the case. It will be understood also that a quantity of the refrigerant will remain in the supplemental refrigerant compartments between the walls 13 and 21. Inasmuch as the wall 19, by means of the baffle walls 23 and 24, is within the influence of the circulating area of the display compartment of the refrigerator, there will be a continued circulation across the baffle walls carrying to the interior of the case the cool currents 30 of air and maintaining a substantially uniform temperature both in the upper and in the lower strata of the display section of the refrigerator.

In order to obtain the maximum effect 35 from the refrigerating liquid after it has melted, that portion thereof that passes onto the plates 24 and the wall 20 is drained into a trough 26 disposed at the lower edge of the wall 20 and which inclines backwardly to the back wall of the case. The trough 26 discharges into a pipe 27 that runs longitudinally of the back of the case and has an inwardly curved forward end 28 terminating over the drip pan.

65 The chamber formed by the walls 21 and

22 may be drained onto the upper plate 24 by a pet cock or valve 29 of any suitable kind. The lower chamber is drained through a pet cock or valve 30 into a trough 31 that inclines forwardly and discharges into a 70 pipe 32 having an inwardly turned end 33 likewise discharging into the drip pan.

In Fig. 7 is a detail view of the preferred form of connection between the troughs 26 and 31 and their respective discharge pipes 75 27 and 32. This connection comprises a tube 34 vertically disposed in the troughs, the lower end of the tube extending above a slot 35 formed in the upper wall of the discharge pipes. The drip pan into which the 80 pipes 27 and 32 discharge comprises a rectangular container 36 supported on legs 37 by the bottom wall of the case substantially at the center thereof. In order to increase the refrigerating effect of the drip pan it is 85 made with a central open flue 38. The drip pan has a vertically disposed drain pipe 39 that discharges into a trap 40 formed in the bottom wall of the refrigerator case which is drained by a discharge pipe 41.

90 It will thus be seen that the construction described provides for circulating from the refrigerant containers cooling currents of air at different elevations in the refrigerator case. It will also be seen that the construction provides means for distributing the refrigerant throughout the case so that the cooling effect of the refrigerant, not only in the form of ice and salt but as well, after the ice has melted and the brine formed, is 95 utilized in cooling in distributed areas the entire case. It will be noted also in connection with the drain arrangements for the refrigerant containers that the drip is distributed over exposed surfaces of the baffle 100 plates so that they will be kept free from frost and so that the passage ways and openings between the baffle plates will be kept from clogging by the flow of the drip therethrough.

110 I am aware that the invention may be varied in various particulars without departing from the spirit and scope thereof, and therefore do not limit myself unessentially.

What I claim and desire to secure by Letters Patent is:—

1. A refrigerator comprising a case having a central display compartment, a refrigerant container located at each end of the case, supplemental refrigerant containers within each refrigerant container, a series of baffle walls forming air circulating passages located between said supplemental refrigerant containers that communicate with the central display compartment of the case at one end thereof and within the upper area, a second series of transverse baffle walls in each refrigerant container disposed beneath said supplemental refrigerant containers, said second-named series of baffle 120 walls forming air circulating passages located between said supplemental refrigerant containers and the interior of the case, a trough disposed at the lower edge of the back wall of the case, a pipe 125 running longitudinally of the back of the case and having an inwardly curved forward end terminating over the drip pan, a pipe 130

- walls in each refrigerant container adapted to receive liquid therefrom, a drip pan located at the bottom of the display compartment of the case, and troughs connected with the side of the refrigerant containers adjacent to the display compartment and at an elevation above the bottom of the case. 5
2. A refrigerator comprising a casing having a display section and a refrigerating section, a refrigerant container located in the refrigerating section adapted to contain refrigerating liquid, a supplemental container within said refrigerant containers, a series of baffle walls forming air circulating passages located adjacent said supplemental refrigerant containers, said passages communicating with the display section, a second series of transverse baffle walls in said refrigerant container disposed beneath said supplemental refrigerant containers, said second named series of baffle walls in said refrigerant container adapted to receive a liquid therefrom, and troughs connected with the side of the refrigerant container adjacent to the display section and at an elevation above the bottom of the case. 10
3. A refrigerator comprising a case, a refrigerating compartment at one end of the case, a display compartment adjacent thereto, a refrigerant container within the refrigerating compartment, internal pockets formed in the upper part of the refrigerant container, said pockets adapted to receive and hold a quantity of refrigerant, an air chamber between said pockets, open troughs running transversely of the side of the refrigerant container adjacent to the display compartment of the refrigerator case adapted to receive liquid discharged from the refrigerant container through said air chamber, an open drip pan located in the bottom of the display compartment of the refrigerator case, and pipes communicating the troughs with the open drip pan. 15
4. A refrigerator comprising a case having a central display compartment, refrigerant containers mounted in said case at each end of said display compartment, pockets formed in said refrigerant containers located adjacent to the top thereof and upon the side adjacent to the display compartment of the refrigerator case, a series of downwardly inclined spaced baffle walls formed within each refrigerant container forming air passages that communicate with the display compartment of the refrigerator case, and a second series of transverse walls disposed beneath said first-named baffle walls and beneath the pockets formed therein forming air 20
- passages communicating with the display compartment of the refrigerator case, and said walls being arranged to receive liquid from the refrigerant containers. 60
5. In a refrigerator, a refrigerant container, a transverse wall in said container forming horizontally spaced compartments for receiving liquid discharged from the refrigerant container, a series of downwardly inclined baffle walls in each of said compartments the lower one of said series of walls being arranged to receive liquid discharged from said refrigerant container, and means for communicating the upper one of said last-named compartments with the other one thereof. 65
6. In a refrigerator, a refrigerant container having an imperforate bottom wall, a transverse vertical and a horizontal baffle wall in said container forming a supplemental compartment within said refrigerator container, said vertical wall having a series of perforations therein at spaced vertical intervals, separating walls in said supplemental compartment forming an outlet passage that opens to the exterior of said container, and baffle walls in said outlet passage, said baffle walls being inclined downwardly and thereby arranged to receive liquid from said refrigerant container. 70
7. In a refrigerator, a refrigerant container, a transverse and horizontal baffle wall in said container, forming an upper compartment, a separating wall in said upper compartment forming an outlet passage to one end thereof, baffle walls in said outlet passage, said baffle walls being inclined downwardly and arranged in parallel planes, and passages in said vertical wall communicating with the space between said baffle walls whereby the refrigerant in liquid state is discharged on said walls. 75
8. In a refrigerator, a refrigerating compartment formed in the case of the refrigerator, a pull-out refrigerant container arranged to be mounted in said compartment, an exterior flange on each side of the refrigerant container extending parallel with the back wall and abutting against the opposite walls of the refrigerating compartment, a chamber in the side of said container having communication with said container, and a series of deflecting walls arranged transversely of said internal chamber in spaced parallel planes forming passageways that open outwardly from the refrigerant container on the side thereof opposite to said external flanges. 80
9. In a refrigerator, a refrigerating compartment formed in the case of the refrigerator, a pull-out refrigerant container arranged to be mounted in said compartment, an exterior flange on each side of the refrigerant container extending parallel with the back wall and abutting against the opposite walls of the refrigerating compartment, a chamber in the side of said container having communication with said container, and a series of deflecting walls arranged transversely of said internal chamber in spaced parallel planes forming passageways that open outwardly from the refrigerant container on the side thereof opposite to said external flanges. 85
10. In a refrigerator, a refrigerating compartment formed in the case of the refrigerator, a pull-out refrigerant container arranged to be mounted in said compartment, an exterior flange on each side of the refrigerant container extending parallel with the back wall and abutting against the opposite walls of the refrigerating compartment, a chamber in the side of said container having communication with said container, and a series of deflecting walls arranged transversely of said internal chamber in spaced parallel planes forming passageways that open outwardly from the refrigerant container on the side thereof opposite to said external flanges. 90
11. In a refrigerator, a refrigerating compartment formed in the case of the refrigerator, a pull-out refrigerant container arranged to be mounted in said compartment, an exterior flange on each side of the refrigerant container extending parallel with the back wall and abutting against the opposite walls of the refrigerating compartment, a chamber in the side of said container having communication with said container, and a series of deflecting walls arranged transversely of said internal chamber in spaced parallel planes forming passageways that open outwardly from the refrigerant container on the side thereof opposite to said external flanges. 95
12. In a refrigerator, a refrigerating compartment formed in the case of the refrigerator, a pull-out refrigerant container arranged to be mounted in said compartment, an exterior flange on each side of the refrigerant container extending parallel with the back wall and abutting against the opposite walls of the refrigerating compartment, a chamber in the side of said container having communication with said container, and a series of deflecting walls arranged transversely of said internal chamber in spaced parallel planes forming passageways that open outwardly from the refrigerant container on the side thereof opposite to said external flanges. 100
13. In a refrigerator, a refrigerating compartment formed in the case of the refrigerator, a pull-out refrigerant container arranged to be mounted in said compartment, an exterior flange on each side of the refrigerant container extending parallel with the back wall and abutting against the opposite walls of the refrigerating compartment, a chamber in the side of said container having communication with said container, and a series of deflecting walls arranged transversely of said internal chamber in spaced parallel planes forming passageways that open outwardly from the refrigerant container on the side thereof opposite to said external flanges. 105
14. In a refrigerator, a refrigerating compartment formed in the case of the refrigerator, a pull-out refrigerant container arranged to be mounted in said compartment, an exterior flange on each side of the refrigerant container extending parallel with the back wall and abutting against the opposite walls of the refrigerating compartment, a chamber in the side of said container having communication with said container, and a series of deflecting walls arranged transversely of said internal chamber in spaced parallel planes forming passageways that open outwardly from the refrigerant container on the side thereof opposite to said external flanges. 110
15. In a refrigerator, a refrigerating compartment formed in the case of the refrigerator, a pull-out refrigerant container arranged to be mounted in said compartment, an exterior flange on each side of the refrigerant container extending parallel with the back wall and abutting against the opposite walls of the refrigerating compartment, a chamber in the side of said container having communication with said container, and a series of deflecting walls arranged transversely of said internal chamber in spaced parallel planes forming passageways that open outwardly from the refrigerant container on the side thereof opposite to said external flanges. 115

CLIFFORD F. BOYER.
